Primary Examiner — Robin V Webster*(74) Attorney, Agent, or Firm* — Fletcher Yoder, P.C.(57) **CLAIM**

I claim the ornamental design for a moving bed bioreactor carrier, as shown and described.

DESCRIPTION

FIG. 1 is a perspective view of the moving bed bioreactor carrier of the present invention;

FIG. 2 is a front elevational view of the moving bed bioreactor carrier of FIG. 1, the rear elevational view being a mirror image of the front elevational view shown;

FIG. 3 is a left side view of the moving bed bioreactor carrier of FIG. 1, the right side view, top view and bottom view being essentially identical to the left side view shown; and, FIG. 4 is a perspective view of an alternate embodiment, the edges shown fragmented to indicate non-specified length.
